UNITED STATES PATENT OFFICE.

HORACE M. YOUNG, OF NIAGARA FALLS, NEW YORK.

WOOD-SPLITTING MACHINE.

1,328,471.

Specification of Letters Patent. Patented Jan. 20, 1920.

Application filed September 16, 1918. Serial No. 254,182.

To all whom it may concern:

Be it known that I, HORACE M. YOUNG, a citizen of the United States, residing at Niagara Falls, in the county of Niagara 5 and State of New York, have invented certain new and useful Improvements in Wood-Splitting Machines, of which the following is a specification.

My invention relates to a wood splitting 10 machine, and more particularly to a machine of the portable type.

One of the objects of my invention is the provision of a portable wood splitting machine which can be conveniently moved 15 from place to place for splitting wood to the desired thickness or thicknesses by passing the wood to be split through the machine.

Another object of my invention is to provide a wood splitting machine having means 20 whereby the wood is separated after being split so that pieces larger than the size or sizes desired will be delivered to the feeding end of the machine to be split while the remaining pieces split to the proper sizes are 25 delivered over the rear end of the machine to be corded or otherwise disposed of.

The invention consists in the novel feature of construction and in the arrangement and combination of parts to be hereinafter 30 described and more particularly pointed out in the subjoined claims.

In the drawings,—

Figure 1 is a side elevation of a machine constructed according to my invention.

Fig. 2 is a plan view of the same.

Fig. 3 is a longitudinal section through a portion of the machine near its front end taken on line *a—a*, Fig. 5.

Fig. 4 is a longitudinal section through 40 the rear end of the machine taken on line *a—a*, Fig. 5.

Fig. 5 is an enlarged transverse section taken on line *b—b*, Fig. 1.

Fig. 6 is an enlarged transverse section 45 taken on line *c—c*, Fig. 1.

Fig. 7 is a detail view showing a portion of the wood receiving trough arranged at the bottom of the machine.

Fig. 8 is a detached perspective view of 50 part of the sizing and separating mechanism,

Referring now to the drawings in detail, like numerals of reference refer to like parts in the several figures.

The reference numeral 1 designates the front axle, 2 the rear axle, and 3 the traction and supporting wheels rotatably mounted on the ends of said axles. The front axle 1 comprises a body portion 4, the ends of which are secured in skeins 5 having the axle spindle 6 integral therewith. The body portion 4 has a depression 7 in its upper face between its ends and in this depressed portion a bolster 8 is secured by means of a king bolt 9 which passes through the axle 65 from the bottom and has a reduced threaded portion 10 at its upper end which is threaded into said bolster.

11 designates the reach, or bed, so called since along the same the wood to be cut is 70 adapted to be moved. This reach or bed extends from a point a distance in front of the front axle 1 to a point a distance in rear of the rear axle 2 and it is secured to the bolster 8 by means of bolts or screws 12 and 75 to the rear axle 2 by means of bolts or screws 13. By thus connecting the rear axle 2 with the bolster 8 the latter is prevented from turning and permits the turning of the front axle for steering the machine. 80

The reach or bed 11 is provided with two longitudinally-disposed grooves 14, 15, which are spaced apart, the securing bolts or screws 12 and 13 being countersunk below the bottoms of these grooves. Overhanging 85 the opposite side walls of each of these grooves are guide bars 16 which are secured to the top of the reach or bed 11 in any approved manner. The splitting mechanism is mounted on a superstructure 17 which 90 comprises four uprights 18, two of which are secured to the bolster 8 near opposite ends and two to the rear axle 2. These uprights are therefore arranged in pairs at each side of the machine which are connected at their upper ends by means of longitudinal shaft supports 19. The lower ends of the uprights 18 at the front of the machine are fastened to the bolster 8 by means of braces 20 applied to the uprights at the 100 inner and outer sides thereof and bolted thereto by means of the bolts 21. These

braces are secured to the bolster 8 by means of bolts 22. Similar braces 23 are provided at the lower ends of the uprights 18 at the rear of the machine, these braces being secured to the rear axle in the same manner that the braces 20 are secured to the bolster 8. The braces 23 are also secured to the uprights 18 at the rear of the machine by means of bolts similar to the bolts 21 which fasten the braces 20 to the uprights at the front of the machine. In addition to the braces, straps 24 are passed around the bolster and extend up in contact with the front and rear faces of the uprights 18 at the front of the machine, and similar straps 25 are applied to the rear axle 2 and lie in contact with the front and rear faces of the rear uprights. The straps 24 and 25 are secured to the uprights by means of bolts or screws 26, as best shown in Fig. 6.

The longitudinal shaft supports 19 rest upon the upper ends of the uprights 18 and are secured thereto by means of straps 27, as clearly shown in Figs. 1 and 5. Wood cutters or splitting disks 28, 29, 30 are arranged directly above the reach or bed 11, these disks being of successively larger diameter from the front to the rear of the machine. Each cutter or disk is mounted on a shaft 31 journaled in bearings 32 secured to the under side of the shaft supports 19. The bearings 32 of the shafts on which the disks 28 and 30 are mounted have angular extensions 33 by means of which the upper ends of the uprights 18 are braced to the shaft supports 19.

Each of the shafts 31 has collars 34 secured thereto which bear against the inner sides of the bearings 32 in which the shaft is mounted. The wood cutters or splitting disks are positioned on said shafts centrally between their ends and each is retained in position by collars 35 secured to the shaft supporting the cutter and bears against opposite sides of the latter. Each cutter is disk-like in formation and tapered from its central portion outwardly to its periphery to provide a knife edge for the same, said central portion being widened in the cutters 28, 29 to provide extending hub ends 36 against which the collars 35 bear.

The cable wheels or sheaves 37 are provided at the front end of the machine in line with the longitudinal grooves 14, 15 therein, and similar cable wheels or sheaves 38 are provided at the rear end of the machine, these being also in alignment with said grooves.

Brackets 39 are provided which extend forwardly from the front end of the reach or bed 11 and in said brackets the axle 40 of the front cable wheel is journaled. Brackets 41 also extend rearwardly from the rear end of said reach or bed in which

the axle 42 of the rear cable wheels 38 is journaled, said brackets 39 and 41 being secured to opposite sides of said reach or bed.

The cable wheels 37, 38 of the reach or bed are arranged in pairs, each wheel at the front being mated with a wheel at the rear and around each pair of these wheels an endless cable 43 passes. While I have shown cables passing around said cable wheel, these elements of my apparatus may be termed wood feeding belts, since it is possible to substitute chains or equivalent means for the cables. Each of the cable wheels, which may be broadly considered feeding wheels, is preferably provided with peripheral pockets or depressions 45 into which fit feeding lugs or pushers 44 secured to the cables. Each of these feeding lugs is formed of two parts 46, 47, and at regular intervals I have shown feeding lugs provided with extensions 48 at their feeding or pushing ends.

Each part of a feeding lug is provided with a semi-circular groove which forms an opening through the lug when the parts thereof are secured together, and in these openings the cables 43 are secured. These lugs are secured to each cable at regular intervals so that in passing over the cable wheels they will enter the pockets or depressions 45 in said wheels. It is of course understood that when chains or other equivalent means is substituted for the cables, the contacting faces of the two parts of each lug will be grooved to conform to the cross sectional shape of the chain or other substituted element. These lugs are also provided at opposite sides with grooves 49 to receive the overhanging guide bars 16, these grooves being partly formed in each part of each lug. The two parts of the lugs are secured together and the lugs fastened to the cable or other feeding element by means of a bolt 50 passing through one part and taking into the other. By guiding the lugs in the longitudinal grooves 14, 15 of the reach or bed, the cables are held from contact with the bottoms of said grooves.

On the under side of said reach or bed in rear of the bolster 8, depending lugs 51 are provided, these lugs being integral with said reach or bed. Two shaft supports in the form of links 52 are pivotally secured at their upper ends to said lugs and extend from said lugs downwardly and inwardly, and in their lower or forward ends a shaft 53 is mounted, said shaft bearing cable wheels 54 similar to the cable wheels 37, 38. The axis of cable wheels 54 is in a lower plane than the axes of the cable wheels 37, 38, but it will be observed that the rear cable wheels 38 are considerably larger than the cable wheels 37 and 54, this being for

the purpose of bringing the lowermost stretch of the cable in close proximity to the bottom of a wood carrier or trough to be presently described. The cable wheels 54 may be termed "idle" to maintain the feeding cable taut at all times and to keep that portion of said cable between said idler wheels and the rear cable wheels 38 in a horizontal position.

10 Secured to the rear axle 42 is a drive pulley 55 around which a belt may be passed for rotating said shaft and the cable wheels thereon, and through said cable wheels causing the feeding cables to rotate the cable wheels 37 and the idler wheels 54, the movement of said feeding cable being utilized to feed the wood to be split and the split wood of larger sizes than desired, through the machine.

20 The reach or bed is provided centrally with a shallow depression 56 on its upper face, see Fig. 5, in which the wood is moved rearward. The cutting edges of the disks are arranged successively closer to the reach 25 or bed from front to rear so that wood placed onto said reach or bed and carried rearwardly by the feeding cable will be gradually reduced in size under the successive cutting or splitting actions of these 30 disks, the pieces of wood smaller than the size desired being delivered from the rear end of the machine and those that are of larger size being delivered to the sides of the reach or bed to be passed through the 35 machine a second time.

It is to be noted that I have shown the cutters or splitting disks arranged to operate against the wood passed through the machine without driving said cutters or disks, but if 40 desired, these cutters or disks may be driven in any suitable manner from the shaft 42, or otherwise. In either case, however, it will be found that considerable strain is applied to the reach or bed, and for this reason I 45 have shown said reach or bed constructed of metal and provision made for firmly supporting the same on the axles of the machine.

57 designates a wood carrier or trough having a flat bottom 58, and upwardly diverging sides 59, 60. This carrier or trough is supported from the reach or bed 11 by means of bolts 61, these bolts being passed centrally through the reach or bed and extending downwardly through the flat bottom 58. The heads of the bolts 61 are countersunk in the reach or bed so as to avoid obstructing the feeding of the wood along the latter. One of these bolts is arranged in rear of the rear axle and the other in the 60 rear of the front axle and each has a nut 62 secured to its lower ends against which the flat bottom 58 of the carrier or trough rests.

As clearly shown in Fig. 1, each of the rear brackets 41 is secured to a side of the

reach or bed by means of a bolt 63 passed 65 through the front end of the bracket and additional bolts or pins 64 disposed in a plane or planes in rear of said bolt 63. These brackets are of considerable width between their ends and an additional bolt hole 65 70 is provided at a low point of each bracket.

Upon removing the bolts or pins 64, the brackets 41 may be swung upwardly on the bolts 63 to bring the bolt hole 65 of each bracket in line with a bolt hole in the reach 75 or bed into which one of the bolts 64 was threaded. In this manner the rear cable wheels 38 may be elevated. When so elevated, the lower stretch of cable is raised, thereby permitting the carrier or trough 57 80 to be elevated, which is a desirable feature of my invention, since it permits of moving the machine from place to place without having parts thereof sufficiently low to come in contact with obstructions along the road 85 or other path over which the machine may be drawn.

To permit of raising the carrier or trough 57, each of the bolts 61 is provided with one or more diametral openings or pin holes 66, 90 and when lifting the carrier or trough these bolts are moved upwardly to bring the diametral openings or holes 66 therein above the upper face of the reach or bed. When in this position, pins may be passed through 95 these holes, which pins may project from opposite sides of the bolts and rest upon the upper face of the reach or bed. In the drawings I have shown a single pin hole formed in each bolt 61, but additional pin holes may 100 be provided if desired.

Depending from the front and rear axles are hooks 67 into which are adapted to fit rod 68 arranged lengthwise along the upper edges of the sides 59, 60 of said carrier or 105 trough, thus holding said sides elevated. This carrier or trough has its sides hinged to the flat bottom 58, as at 69. The flat bottom 58 and the sides are preferably built up with planks or narrow pieces of wood 110 secured to straps 70 arranged at regular intervals along the length of said carrier or trough, opposite ends of the straps 70 secured to the under side of the flat bottom having hinge members and the lower ends 115 of the straps 70 at the sides having co-acting hinge members, the hinge members of the sides being so formed that one side may be swung underneath the flat bottom 58 and the other side underneath the first-mentioned 120 side, as clearly shown in dotted lines in Fig. 5.

When it is desired to fold the carrier or trough 57, the rods 68 at the upper edges of the sides thereof may be disengaged from 125 the hooks 67 and the bolts 61 may be forced upwardly with the carrier or trough to a sufficient height to permit the sides to be

swung underneath the bottom, or any other method may be resorted to for folding the sides underneath the bottom.

The braces 20 applied to the inner sides 5 of the uprights 18 have upstanding webs 71, the upper edges of which incline inwardly, and resting upon said webs are boards 72 which serve as guards, the upper 10 faces of said boards at their inner edges being arranged flush with the upper sides of the guide bars 16. By reason of these boards being applied to said webs they incline inwardly from their outer edges, and any tendency of the wood carried along 15 the reach or bed to roll outwardly is prevented thereby.

The reach or bed 11 is provided at its front end with a downward extension 73 to which the front end of a brace arm 74 is 20 secured, the rear end of said brace arm having the king bolt 9 passed therethrough.

The front axle is provided near each end with a pair of forwardly extending spaced lugs 75 in which the rear ends of two inwardly diverging steering bars 76 are pivotally secured, the front ends of said bars being pivotally secured to the ends of a cross steering bar 77 by means of bolts 78. Said cross steering bar is pivotally secured 30 between its ends to the downward extension 73 of the reach or bed by a bolt 79 passing through said cross bar, through the front end of the brace arm 74 and into said downward extension. The cross steering bar 77 35 is provided near each end with a depending lug 80 to each of which the rear end of one of the side bars of a hound 81 are secured, a pole 82 being secured to the front end of said hound.

40 The carrier or trough 57 is arranged with two channels or ways 83 formed by longitudinally-disposed boards 84 secured centrally to the upper side of the flat bottom 58 of said carrier or trough, the lower 45 stretch of one of the cables or wood feeding elements traveling through one of said channels or ways, and the lower stretch of the other cable or wood feeding element through the other channel or way, as clearly 50 shown in Fig. 6. The boards 84 are separated, as at 85, and in the space between adjacent ends of these boards and in line therewith, the rear supporting bolt 61 is positioned. Between the front end of the 55 front board 84 and the idlers or cable wheels 54, a protector 86 is arranged, this protector having the front supporting bolt 61 passed therethrough and having also legs 87 which 60 position the body portion of said protector above the lower stretches of the feeding elements so that these elements may pass underneath said body portion.

Said protector has its sides flared forwardly and serves to deflect the pieces of wood laterally in opposite directions so as

to prevent them from coming in contact with the idlers, thereby avoiding wedging of the wood in the trough. The pieces of wood deflected laterally are forced over the front edge of the trough by the pieces advancing while still engaged by the wood-feeding belt. It is apparent therefore that the split pieces of wood cannot become wedged in the trough and the feeding parts of the machine are consequently at no time subjected to undue strains.

A pin 88 is passed through the front supporting bolt 61 and bears against the upper side of said protector. Said pin serves to hold said protector against accidental upward movement along said belt but is withdrawable to permit of elevating the protector when the rear cable wheels 38 are swung upwardly with their supporting brackets so as to permit the lower stretches 85 of the feeding elements to assume an elevated position with the carrier or trough.

At the rear of the machine, directly in rear of the largest wood cutter or splitting disk, a combined sizing and separating device is provided. This device comprises a standard or supporting member 90 in the form of a separator which is secured to the reach or bed of the machine in any approved manner. This separator is provided with a 95 long vertical rear edge 91 and a short vertical front edge 92, the front edge being sharpened so that the pieces of wood split by the cutters or disk and particularly the wood split by the rearmost or largest cutter 100 or disk is moved in contact with this separator and the parts thereof fed to opposite sides of the separator 90. If any of the wood reaching this point is not entirely split, this separator will serve to completely 105 split the same while forcing the wood rearwardly, as the sharpened or knife edge of the separator is in direct line with the cutting edges of the wood cutters or disks.

The separator 90 is inclined downwardly 110 and forwardly from the upper end of its rear edge a short distance, as at 93, and then curved, as at 94, to conform to the curvature of the peripheral cutting edge of the rearmost or largest cutter or disk 30. This 115 arrangement positions the front cutting edge of the separator directly beneath the rear portion of the largest cutter or disk.

The separator has lugs 95 extending rearwardly from its rear edge and pivotally 120 secured to these lugs are gates 96 extending in opposite directions from the separator so as to be positioned transversely over the cable feeding elements 43. The outer ends of these gates are therefore free and 125 the gates are adapted to swing rearwardly. They are, however, retained in transverse position by springs 97 coiled around the pivot pins 98 passing through the lugs 95 and coöperating lugs 99 formed at the inner 130

ends of the gates. These gates are provided with rearwardly extending stop lugs 100 at their outer ends, which are adapted to limit the rearward and inward swinging 5 movements of the gates by coming in contact with a stop 101 secured to the reach or bed and positioned in rear of the separator 90.

It is to be noted that the lower edges of 10 these gates are disposed a certain distance above the reach or bed and that the gates are widened at their outer ends, as at 102, so as to form openings 103 through which the split wood may pass. Wood cut to larger 15 size than these openings will therefore engage the front faces of the gates and cause the same to swing rearwardly. The gates, due to their swinging rearwardly, will direct the larger pieces of wood laterally and over the opposite sides of the reach or bed. For 20 this purpose the rear brackets 38 are provided at their upper ends with outstanding webs 104, onto which pieces of wood larger than that desired is fed and from which webs the wood drops into the carrier or 25 trough to be moved forward by the cable 43 to the front end of the machine, where it is again placed upon the reach or bed to be moved rearwardly and cut or split to smaller sizes. The gates will in themselves 30 serve to separate the wood into two grades, one grade being of sizes capable of passing underneath the narrow inner portion of the gates between the outer depending or widened portions 102 thereof; and the other 35 grade including all larger sizes.

Since, however, it is oftentimes desirable to use only pieces of wood that are considerably smaller than the openings 103 formed beneath the gates, I have provided adjustable sizing means arranged to size the wood 40 in two directions as it is delivered along the reach or bed; that is, in height or width. For this purpose, each gate is provided with a gage 105 having a flat horizontally-disposed gaging portion 106 and a slotted vertically-disposed securing portion 107. The securing portions of these gages are placed 45 against the rear faces of the gates, and bolts 108 pass through the slots of the same and fasten into the gates. The flat horizontally-disposed gaging portions 106 may therefore be positioned the desired distance 50 above the reach or bed so that they serve to gage the thickness of the pieces of wood vertically as they are fed along said reach or 55 bed 11 and may therefore be termed "top gages". Additional gages 109, which may be termed "side gages" are provided to 60 gage the thickness of the pieces of wood laterally. These side gages 109 are adjustably secured to the under side of the depending or widened portions 102 at the outer ends of the gates, by means of bolts 110. The side gages extend inwardly from 65 the depending or widened end portions of

the gates and the front edges thereof are gradually curved rearwardly. The inner ends of the side gages are increased in depth, as at 111, to provide contact portions and to bring the said contact portions beneath 70 the lower faces of the top gages 103.

Each of the side gages has a slot 112 along its front marginal portion, and a slot 113 is provided along its rear marginal portion, these slots converging and merging 75 into a single slot 114 at the outer ends of the side gages. This side gage may be positioned so that the bolts 110 may be passed through the slot 112, or so that one of said bolts may be passed through each of the 80 slots 112, 133, thus permitting the side gages to be positioned on the gage at different angles. This being necessary due to the fact that when wood larger than the desired size comes in contact with the contact 85 portions 111 of said side gages, the gates are swung rearwardly and the angles of the front edges of the side gages are such that the wood is directed outwardly over the ledges 104 formed on the rear brackets 41, 90 from which it will drop into the carrier or trough and be moved forwardly to the front end of the machine to be passed through the splitting mechanism a second time.

The wood is placed upon the reach or bed 95 at the front end of the machine to be engaged by the lugs or pushers 44 secured to the cables or endless feeding elements 43, and by these lugs or pushers the wood moved rearwardly along said reach or bed, 100 engaging the cutters or splitting disks 28, 29, and 30 in succession, provided of course that the pieces of wood are sufficiently large to come in contact with the smallest disk 28. The smaller pieces of wood may, however, 105 come in contact with the disks 29, 30 only, but such pieces that may pass underneath the intermediate cutter or disk 29 without coming in contact therewith, will be engaged by the largest cutter or disk 30 and be split thereby. The large pieces will be fissured by the smallest cutter or disk 28, and in passing in contact with the intermediate or medium sized cutter or disk 29 may be split in two 110 along the fissures formed by the smallest disk, and if not completely split in two by the intermediate disk, will be engaged by the largest disk 30, which in most cases insures complete splitting of the wood. Some pieces may, however be split yet the 115 parts thereof joined together by splinters, and when such pieces come in contact with the separator 90, the parts thereof will be completely separated thereby. The wood split in this manner will be forced along the 120 reach or bed, the pieces thereof passing at opposite sides of the separator.

Pieces split to a given size or smaller will pass underneath the gates 96 or the gaging devices secured to the gage, as the case may 130

be, and be delivered by the cables or feeding elements 43 over the rear end of the machine, to be corded or otherwise disposed of. The pieces of wood, however, that are 5 not small enough to pass underneath the gates or the gaging devices applied to the gates, as the case may be, will cause the gates to swing rearwardly and inwardly to 10 form deflectors, the pieces of wood being deflected by said gates or the gaging devices thereon over the sides of the reach or bed so that they fall into the trough or carrier 15 57, the lugs or pushers on the lower stretches of the cables or feeding elements 43 engaging the pieces of wood and moving them forward to the front end of said trough or carrier where they are delivered in a convenient position to be again placed upon the 20 reach or bed at the feeding end of the machine to be passed through the machine a second time. The protector 86 is provided 25 near the front end of the trough or carrier to deflect the wood so as to position the same lengthwise with a view of having the lugs or pushers on the cables or feeding elements engage the ends of said pieces; also 30 to protect said cables or feeding elements against unnecessary strain by reason of pieces of wood lodging crosswise and becoming wedged in such positions.

While I have shown three wood cutter or splitting disks, I do not wish to limit myself to this number, as a single disk or any other number may be used without departing 35 from the spirit of my invention. Other changes and modifications may also be resorted to under the principle involved in this invention, as the drawings are to be considered only as representing what I now 40 consider the best embodiment of my invention. It is therefore intended that all matter contained in the above description or shown in the accompanying drawings shall 45 be interpreted as illustrative and not as limiting, and that many changes could be made without departing from the scope of this invention.

What I claim is:—

1. In a wood splitting machine, a support, a wood splitting element in operative 50 relation to said support, means for feeding wood to said wood splitting element, and means for gaging the wood to size to separate the split pieces larger than a given size 55 from the pieces of or smaller than the given size.

2. A wood splitting machine, comprising a longitudinal bed onto one end of which the wood to be split is placed, means for 60 feeding the wood lengthwise along said bed, wood splitting elements arranged along said bed and spaced therefrom to split the wood fed along the bed, and means for separating the split pieces larger than a given size from 65 those of or smaller than the given size.

3. A wood splitting machine, comprising a longitudinal bed, an endless feeding element passing lengthwise around said bed, the upper stretch of which is adapted to feed wood from the front end of said bed 70 to the rear end thereof, splitting elements adapted to split the wood fed along said bed, means near the rear end of said bed for separating the wood and delivering the pieces larger than a given size over the side 75 of the bed, the lower stretch of said feeding element being adapted to feed the wood larger than the given size to the front end of the machine to permit of passing the same through the machine a second time. 80

4. A wood splitting machine, comprising a longitudinal bed, a trough beneath said bed and wider than the same, an endless feeding element traveling lengthwise around said bed and having one stretch thereof 85 passing along the top and another stretch beneath the bottom of said bed, wood splitting elements above said bed against which the wood to be split is carried by the upper stretch of said feeding element, and means 90 for separating the split wood to direct the pieces larger than a given size over the sides of said bed and into said trough to be carried forward by the lower stretch of said feeding element, said separating means permitting the split wood of and smaller than 95 the given size to be delivered over the rear end of said bed.

5. A portable wood splitting machine, comprising a wheeled reach or bed, a trough 100 beneath said reach or bed and wider than the same, an endless feeding element passing around said reach or bed, wood splitting elements above said reach or bed and spaced different distances therefrom, and means at 105 the rear end of said reach or bed for gaging the wood according to size and delivering split pieces larger than a given size into said trough to be returned to the front end of the machine by the lower stretch of said 110 feeding element.

6. A wood splitting machine, comprising a reach or bed, axles on which said reach or bed is secured, wheels rotatable on said axles, a trough beneath said reach or bed and 115 wider than the same, means for supporting said trough from said reach or bed, a plurality of wood splitting disks of different sizes arranged above said reach or bed and having their effective cutting edges spaced 120 successively closer to said reach or bed toward the rear end of the machine, spaced endless feeding elements passing lengthwise around said reach or bed and having lugs or pushers secured thereon, and means in 125 rear of said splitting disks for separating the split wood to permit pieces of and smaller than a given size to pass therethrough and to compel pieces larger than the given size to be delivered over the sides 130

of said reach or bed and into said trough, the wood delivered into said trough being carried by the lower stretches of said feeding elements to the front end of the machine 5 so as to be again passed through the machine and be split to smaller size or sizes.

7. A wood splitting machine, comprising a bed provided with a pair of longitudinally-spaced grooves, a pair of cable sheaves at 10 each end of said bed provided with peripheral pockets, cables passing around said sheaves, each cable having one stretch thereof adapted to move rearwardly through one of said grooves and one stretch thereof to 15 move forwardly beneath said bed, lugs secured at regular intervals to each of said cables and adapted to enter the pockets in said sheaves, means for rotating one pair of said sheaves to cause movement of said cables, a trough situated beneath said bed and wider than the same, a plurality of splitting disks arranged above said bed, and means at the rear end of said bed to separate the 20 split wood and feed the pieces larger than a given size into said trough to be carried by the lugs on the lower stretches of said cables forwardly in said trough to the front end of the machine.

8. A portable wood splitting machine, 30 comprising a reach or bed, axles to which said reach or bed is secured, wheels rotatable on said axles, a trough underneath said bed and carried thereby, means for raising said trough, cable sheaves at the front and rear 35 ends of said bed, a cable passing lengthwise around said bed and around said sheaves with the lower stretch of the cable normally a distance from the under side of said bed, means for rotating the sheaves at one end of 40 said bed, means for elevating the cable sheave at one end of said bed to raise the lower stretches of the cables and permit said trough to be elevated, projections on said cables adapted to engage pieces of wood to 45 be split and force the same along said reach or bed, a wood splitting disk rotatably arranged above said bed against which the wood to be split is forced, and means for separating the split wood to cause pieces 50 larger than a given size to be delivered into said trough and by the lower stretches of said cables be carried forwardly along said trough to the front end of the machine.

9. A portable wood splitting machine, 55 comprising a wheeled bed, a trough beneath said bed, bolts carrying said trough and having their upper headed ends countersunk in said bed, said bolts being slidable through said bed and each having a pin hole a distance from its upper end through which 60 pins are to be passed when said bolts are moved upwardly to bring said pin holes above the top surface of said bed, a splitting element arranged above said bed, means for 65 forcing the wood along said bed to engage

said splitting element and be split thereby, and means in rear of said splitting element to cause wood larger than a given size to be delivered into said trough.

10. A portable wood splitting machine 70 comprising a reach or bed, axles to which said reach or bed is secured, wheels on said axles, splitting disks above said reach or bed, means for feeding wood to the successive splitting disks, a trough beneath said 75 bed adapted to be elevated when transporting said machine, and means for holding said trough in elevated position.

11. A wood splitting machine comprising a reach or bed, axles to which said reach or 80 bed is secured, wheels mounted on said axles, a trough vertically adjustable underneath said bed, wood splitting elements above said bed, means for feeding wood along said bed to be split by said splitting elements, and 85 means in rear of said splitting elements to direct the split wood larger than a given size into said trough, said feeding element being also utilized to force the wood delivered into said trough along the trough to 90 the front end of the machine.

12. A portable wood splitting machine, comprising a wheeled body portion including a bed, wood feeding mechanism movable lengthwise along said bed, wood splitting 95 elements above said bed, and a trough beneath said bed and carried thereby, said trough having a bottom and sides pivotally secured to opposite longitudinal edges of said bottom, and means for holding the sides 100 in elevated positions.

13. A portable wood splitting machine, comprising a wheel-supported bed, wood splitting elements supported above said bed, means for feeding wood to be split along 105 said bed, and a trough suspended from said bed and wider than the latter, said trough having a bottom and upwardly diverging sides hinged to said bottom and arranged to swing underneath said bottom with one 110 side swung under the other, and means for holding said sides in elevated positions.

14. A portable wood splitting machine, comprising a bed, axles to which said bed is secured, wheels on said axles, wood splitting mechanism above said bed, a trough suspended from said bed and having a bottom and upwardly diverging sides hinged to said bottom, each side having a rod secured to its upper edge, and hooks secured 115 to said axles onto which said rods are adapted to be hung.

15. A wood splitting machine having a longitudinal bed, wood splitting elements above said bed, means for feeding wood 125 along said bed, a separator secured to the upper side of said bed in alignment with said wood splitting elements, and gates hinged at their inner ends to said separator and having portions thereof spaced from 130

said bed to provide openings through which the split pieces of wood of and smaller than a given size are passed, said gates serving to deflect pieces larger than the given size laterally.

16. A wood splitting machine, comprising a support, wood splitting means, means for feeding wood to be split to said splitting means, a separator in rear of said splitting means, and means carried by said separator to gage the split wood and to separate pieces of and smaller than a given size from pieces larger than the given size.

17. A wood splitting machine, comprising a support, means for splitting wood above said support, feeding mechanism for feeding the wood to be split by said splitting means, a separator in rear of said splitting means, gates pivotally secured at their inner ends to said separator and adapted to swing rearwardly and inwardly, and gaging means secured to said gates.

18. In combination, in a wood splitting machine, means for splitting wood, means for separating wood according to sizes after being split, and means for automatically returning pieces larger than a predetermined size to the feeding end of said machine.

19. In combination, in a wood splitting machine, means for splitting wood, means for separating pieces of split wood of and smaller than a given size from pieces larger than the given size, and means for automatically returning pieces larger than a predetermined size to the feeding end of said machine.

20. In combination, in a wood splitting machine, wood splitting means, means to feed wood to be split to and beyond said wood splitting means, a support in rear of said wood splitting means, gates hinged to said support and extending in opposite direction therefrom, and means secured to each gate for gaging the split wood in width and height.

21. In combination, in a wood splitting machine, means for splitting wood, means for feeding the wood to be split to and in rear of said wood splitting means, a support in rear of said wood splitting means, a gate hinged at one end to said support and having a depending portion at its other end, means secured to said depending portion for gaging the width of the wood, and means secured to the gate between said depending portion and its pivoted end for gaging the height of the wood.

22. In a wood splitting machine, a longitudinal support, wood splitting elements above said support, means for feeding wood to be split along said support, a separator secured to said support in rear of said wood splitting elements and having a sharpened front end, gates secured to the rear end of said separator and extending laterally in

opposite directions therefrom, each gate having a depending portion at its outer end, an adjustable gage member secured to each gate between its pivoted end and the depending portion thereof, and an adjustable gage member secured to the depending portion of each gate and provided at its inner end with contact portions.

23. A wood splitting machine, comprising a longitudinal bed, wood splitting means above said bed, means for feeding wood to be split along said bed, a separator in rear of said wood splitting means, and a pair of oppositely-directed gates pivotally secured at their inner ends to said separator and having depending portions at their outer ends.

24. A wood splitting machine, comprising a longitudinal bed, wood splitting means above said bed, means for feeding wood to be split along said bed, and a pair of oppositely-directed gates pivoted at one of their ends and having depending portions at their other ends.

25. A wood splitting machine, comprising a longitudinal bed, wood splitting means above said bed, means for feeding wood to be split along said bed, and a gate disposed normally at a right angle to the line of travel of the wood through the machine, said gate being pivoted at one end in rear of said wood splitting means and having a depending portion at its other end to gage the thickness of the split pieces in one direction.

26. In a wood splitting machine, a support, a gate hinged to said support, and gaging means comprising two gaging members secured to said gate, one gaging member comprising a horizontally-disposed gaging portion and a slotted vertically-disposed securing portion adjustably secured to said gate and the other gaging member extending inwardly from the outer end of said gate and being gradually curved rearwardly at its front edge with the inner ends thereof increased in depth to provide contact portions.

27. In a wood splitting machine, gaging mechanism comprising a gate pivoted at one end and having a depending portion at its other end, a gaging member secured to said gate between its pivoted end and said depending portion and comprising a slotted vertically-disposed securing portion adjustably secured to said gate and a flat horizontally-disposed gaging portion, and a second gaging member secured to the lower edge of said depending portion and having its front edge curved rearwardly with the inner end of the gage increased in depth to provide a contact portion, said second gaging member having inwardly diverging slots terminating in a single slot at their outer ends and through one or more of which

slots bolts are passed to position the gaging member at the desired angle for deflecting pieces of wood larger than a given size in one direction while permitting wood of and 5 smaller than the given size to pass said gaging member.

28. A wood splitting machine, comprising a longitudinal bed, wood splitting elements supported above said bed, means for feeding wood to be split along said bed including a pair of endless cables, a trough beneath said bed having an upstanding board situated between the lower stretches of said cables, idlers in contact with which said 10 cables travel, and means to protect said idlers so as to guard against pieces of wood carried along said trough becoming wedged against said idlers.

29. A wood splitting machine, comprising a longitudinal bed, wood splitting elements supported above said bed, means for feeding wood to be split along said bed including a pair of endless cables, two pairs of cable 20 wheels around which said cables pass, a pair

of idlers situated between said two pairs of 25 cable wheels and in contact with which said cables pass, a trough beneath said bed having an upstanding board situated between the lower stretches of said cables, and a protector situated between said upstanding 30 board and said idlers and having forwardly flaring sides, as and for the purpose described.

30. A wood splitting machine, comprising a longitudinal bed, wood splitting elements 35 supported above said bed, means for feeding wood to be split along said bed including a pair of endless cables, a trough beneath said bed, supporting bolts suspended from said bed and supporting said trough, 40 idlers situated between said bed and the bottom of said trough, and a protector secured to one of said supporting bolts and arranged in rear of said idlers, said protector having forwardly flaring sides, as and 45 for the purpose described.

In testimony whereof I affix my signature.
HORACE M. YOUNG.
